UNITED STATES PATENT OFFICE

2,093,276

SLIDE FASTENER

Nathan Kase, New York, and Louis Wiesenfeld, Brooklyn, N. Y., assignors to Glida Corporation of America, New York, N. Y., a corporation of New York

Application January 14, 1936, Serial No. 59,014

3 Claims. (Cl. 24—207)

This invention relates to improvements in fastening devices, and more particularly to the kind of slide fastening devices set forth in our prior Letters Patent No. 2,013,706, granted September 10, 1935.

In our prior patent above mentioned, the fastening device shown therein consists of a plurality of slide clip members connected at spaced distances along a flexible element. The slide clip members when in use upon the beaded edges of the walls of an opening to be closed are intended to be moved to an open position to one end of such opening with the clip members in contact with each other, but due to the connection of the flexible element by the formation of eyes at the inner end of one of the sides of the clip members, difficulty has been experienced in causing the clip members to assume a position in parallel contacting relation for the reason that there was insufficient space between the eyes of the meeting clips to accommodate the adjacent bends of the flexible element. This condition resulted in causing the outer ends of the clip members to abut while the inner ends assumed a spaced apart relation, thus preventing the said clip members from assuming a compact uniform, parallel relation. Therefore, one of the features of the invention resides in a novel construction of clip slide member which when a number of them are arranged upon a flexible element at spaced distances therealong, enables the members to assume a maximum compact parallel position one against the other when the fastening device is in opening position.

Another feature of the invention is the provision of a slide fastening device composed of a plurality of U-shaped clips having eyes at the terminal ends of one of their legs through which the connecting flexible element passes and by which the clips are fixedly secured to the flexible element, the opposite sides of the eyes being notched to accommodate the adjacent bends of the joined portions of the flexible element which permits the straight side edges of adjacent clips to be moved into parallel contacting engagement when the fastening device is in use upon an article to be closed thereby.

Other objects of the invention will appear as the following specification is read in conjunction with the accompanying drawing, in which:

Figure 1 is a front elevational view of the improved fastening device in position upon a bag.

Figure 2 is an enlarged vertical transverse sectional view on the line 2—2 of Figure 1.

Figure 3 is a vertical sectional view on the line 3—3 of Figure 2.

Figure 4 is a plan view of a plurality of fastening clips showing the same in intimate contact and looking in the direction of their inner ends, the connecting chain being omitted for the sake of clearness.

Figure 5 is a detail perspective view of one of the fastener clips per se, and prior to its attachment to the connecting chain.

Figure 6 is a plan view of the clip in a flattened condition prior to the bending of the same to the desired U-shape.

Referring to the drawing by reference characters, the numeral 10 designates a bag, pouch, or other like article having an opening to be closed, the walls of the mouth of which may be spread apart and are provided with beads 11—11 arranged parallel and in side by side relation. The fastening device is designated in its entirety 15 by the letter A and includes a plurality of U-shaped clip members 12 connected together along one of their sides by a flexible element in the form of a chain 13. One of the end clips 12 and designated at B is tightly secured to the beaded edges 11 of the article 10 and constitutes an anchor clip, whereas the remaining clip members 12 are freely slidable lengthwise of the beaded edges and when spread out along the beaded edges as shown in dotted lines in Figure 1, they 20 assume equi-distant spaced relation due to the fact that the clips are respectively connected to the chain 13 at like spaced intervals. Thus in the operation of the slide fastener, the clips 12 pull away from the anchor clip B when it is desired 25 to close the opening in the article 10 and are moved to an open position against the anchor clip B into bunched formation as shown in full lines in Figure 1 to facilitate access to the article 30 10 through the opening therein.

Each of the U-shaped fastener clips 12 is formed from a single blank of stiff bendable metal as shown in Figure 6 of the drawing, and the blank is of flat elongated configuration having parallel side edges 14—14, rounded ends 15—15 45 and a reduced neck 16 adjacent one of the rounded ends which is formed by notching or cutting away opposite sides of the material as at 17. The blank is folded upon itself within the range between the dotted lines 18—18 so as to assume a substantially U-shaped configuration as shown in Figure 5. The bending of the blank into U-shape provides a bight portion 19 and spaced legs 20 and 21. The notched end of the blank constitutes an extension of the leg 21 and is folded inwardly

substantially on the dotted line 22 to provide a restricted mouth at the open end of the U-shaped clip, after which that portion of the blank beyond the in bend, namely the neck 16 and the head 5 23 is bent outwardly and inwardly into an eye 24. When the eyes 24 are formed, the same lie inwardly of the plane of the outer flat surface of the leg 21 while the notches or cut away portions 10 17 are at the outer bends thereof. Thus the bottoms of the eyes are of less width to provide ample space between the eyes when the clips 12 are in bunched position one against the other to accommodate the bends or adjacent links of the chain at the point where the fastener clips are 15 secured to the chain. This space or gap between adjacent eyes 24 is clearly illustrated in Figures 3 and 4 of the drawing, and permit the straight side edges 14 of adjacent U-shaped clips 12 to flatly contact in order that the clips may assume 20 a parallel relation one against the other when moved to their open position as shown in full lines in Figure 1 of the drawing. The head portions 23 after the eyes are formed imparts the appearance when looked at in side elevation, that the 25 eyes are of the same width throughout as the body of the clips, thus maintaining the straight side effect and forming a continuous uninterrupted appearance when the clip members are in bunched open position as seen by reference to Figure 1. 30 Furthermore, the eyes 24 which serve to connect the clips to the chain are formed beneath the inwardly bent portions of the legs 21 to position the eyes inwardly of the outer face of the legs 21 to avoid any outwardly projecting parts which 35 would make the fastening device bulky or unsightly.

In Figure 5 of the drawing, there is shown one of the clips 12 with its eye 24 in an open position prior to its being finally bent around the fastening chain 13. When the eye is bent to its final position, it firmly grips the chain to prevent possible shifting of the clip relative to the chain.

From the foregoing description, it will be seen that we have provided an improvement over our 45 prior patent above mentioned in that the clip members may be moved into intimate parallel relation with respect to each other which affords a maximum opening of the mouth of the article when access to the interior is desired. This improved feature causes the U-clip members to assume an orderly parallel relation at all times and to cause the slack looped portions of the chain 50 to hang gracefully and uniform as shown in Figure 1 when the clip members are in bunched 55 position against the anchor clip B.

Having thus described the invention, what we claim as new and desire to secure by Letters Patent of the United States, is:—

1. In an article having an opening therein, the walls of which may be spread apart, beads provided on the walls of said opening lengthwise thereof, a fastening device including a flexible element, a plurality of U-shaped clips slidably embracing said beads, each of said U-shaped clips having the free end of one of its legs extending inwardly and provided with an eye at the terminal end thereof, the flexible element passing through the eyes of the respective U-shaped clips and fixedly secured thereto in spaced relation therewith, and notches provided in the opposed side edges of said eyes at the outer portions thereof to accommodate the bends in said flexible element when the U-shaped clips are 10 moved to a bunched position one against the other with portions of the flexible element between said U-shaped clips disposed in loop formation. 15

2. In an article having an opening therein, the walls of which may be spread apart, parallel beads provided on the walls of said opening, a slide fastener device including a plurality of U-shaped clip members embracing said beads, the free end of one of the legs of each U-shaped 20 clip member extending inwardly, eyes at the terminal ends of the inwardly extending portions of the legs of said U-shaped clip members, a chain passing through said eyes, said eyes tightly gripping said chain at spaced distances there- 25 along, said clip members adapted to be spread out along the beads when in closing position and adapted to be moved into engagement with each other when in open position, and notches provided in the ends of said eyes for accommodating certain links of said chain when the clip members are in open position to enable the clip members to assume contact with each other in parallel relation with intermediate portions of the chain extending in loop formation. 30

3. A slide closure device comprising in combination a plurality of U-shaped clip members, each of said U-shaped clip members being formed of a single elongated strip of flat stiff bendable material bent upon itself into U-shape, one of the legs of each U-shaped clip member having an integral extension portion, an eye formed from the extension portion and disposed within the plane of the outer surface of the leg on which it is formed, opposed side edges of the extension portion of each clip member being notched inwardly of the free end thereof, and a flexible element passing through the eyes of the U-shaped clip members and being tightly gripped thereby at spaced distances therealong substantially as and 40 for the purpose specified. 45
